UNITED STATES PATENT OFFICE.

OTTO K. BINDER, OF GENESEO, NEW YORK.

GATE HINGE.

Application filed April 17, 1923. Serial No. 632,624.

To all whom it may concern:

Be it known that OTTO K. BINDER, a citizen of the United States, residing at Geneseo, in the county of Livingston and State of New York, has invented certain new and useful Improvements in Gate Hinges, of which the following is a specification.

In carrying out the present invention, it is my purpose to provide a gate hinge where-
10 in the gate may be raised upwardly for per-
mitting the same to be expeditiously opened
and closed when the ground is covered with
snow or other obstructions are in the way.

A further purpose of this invention is the
15 provision of such a hinge which is comparatively
simple of construction and of such a
nature as to be expeditiously applied to all
types of gates, the invention being further
characterized by its efficiency and durability,
20 the same comprising relatively few parts
and these so correlated as to reduce the lia-
bility of derangement to a minimum.

The nature and advantages of the invention
will be better understood when the fol-
25 lowing detailed description is read in con-
nection with the accompanying drawings,
the invention residing in the construction,
combination, and arrangement of parts as
claimed.

30 In the drawings forming part of this ap-
plication, like numerals of reference indicate
similar parts in the several views, and
wherein:

Figure 1 is a fragmentary elevation of the
35 conventional form of gate secured to a fence
post through the medium of my improved
hinge;

Figure 2 is a top plan view of Figure 1;

Figure 3 is a longitudinal cross section of
40 one of the hinge members; and

Figure 4 is a top plan view of one of the
elements comprised in the hinge member
shown in Figure 3.

Referring to the drawings in detail, 5 in-
dicates a gate and 6 the usual gate post.
These elements, however, are not of the es-
sence of my invention as the same may be
of any convenient construction and are
merely shown for more adequately disclos-
50 ing the relationship of my invention thereto.

Upon the top side of the gate 5 and at the
end thereof adjacent the post 6 are longitudi-
nally extending metallic straps 7, one upon
each side of the gate and being secured to
the gate and to each other through the
medium of bolt and nut connections 8. The

ends of these strap members 7 extend out-
wardly from the end of the gate and are
provided with aligned openings for receiving
therebetween laterally extending pintles 9
of a collar 10, this collar adapted for posi-
tioning over the vertically projecting end 11
of a bolt 12 extended through an opening
adjacent the upper end of the post 6 and
is secured through this opening through the
medium of a nut 13.

Upon one side of the gate 5 and at the
lower corner thereof adjacent the post 6 is
a plunger casing 14, one end of the same
being closed and provided with an exten-
sion ear 15 whereby this casing is pivot-
ally secured to a bracket plate 16 upon
the gate through the medium of a bolt or
the like 17 extending through an opening
within said ear and within any one of a
number of openings 18 in said plate 16.
The front end of the casing 14 is slideable
within a guide bracket 19 upon said gate
5 and freely movable within the casing 14
is an arm or rod 20, the major portion of 80
the top edge thereof being toothed as at 21.
The front end of this rod or arm 20 is
yoked as at 22 and engaging through open-
ings in the opposite legs of this yoked end
are projecting pintles 23 upon opposite 85
sides of a collar 24. This collar 24 engages
over the vertically projecting end 25 of a
spike 26 that is driven into the post 6 ad-
jacent its lower end.

The front end of the top wall of the 90
casing 14 is open and extending within
this opening is the downwardly bent portion
27 of a spring plate 28 that is riveted
or otherwise secured at 29 to said casing.
This downwardly bent portion is adapted 95
for engaging the teeth 21 of an arm or rod
20 for preventing the inward sliding move-
ment of said arm or rod within the casing.
This spring plate 28 is further provided
with an upwardly or rearwardly extend-
ing portion 30 that is connected to one
end of an operating rod 31 that extends
laterally and upwardly to a point adja-
cent the usual gate latch whereby when the
rod 31 is pulled the arm or rod 20 may slide
105 backwards into the casing 14.

In view of the above description it will
at once be apparent that whenever it is
desirable to raise the lower edge of the gate
5 a sufficient distance above the ground sur-
face for permitting the opening and clos-
ing of the same when obstructions are upon
110

the ground the gate may be conveniently raised by raising upwardly upon the free end thereof, the gate being maintained in this position by the said downwardly bent portion 27 of the spring plate 28 engaging one of the teeth of said rod or arm 20, the specific connection between the upper and lower hinge elements of the gate to the post 6 effecting a universal connection of the gate 10 to the post.

It will be obvious to those skilled in the art that I have provided a highly improved form of hinge primarily adapted for association with farm gates, it being, of course, 15 understood that the device may be readily associated with other gates or doors without departing from the spirit and scope of the invention as claimed.

Having thus described my invention, what 20 is claimed is:

A gate hinge including a pair of post carried members, a pair of gate carried members for cooperation therewith for mounting the gate on the post for horizontal swinging movement, and pivoting the 25 gate for vertical adjustment of the free ends,

one of said gate carried members having a tubular housing formed with an ear extending from one end thereof, a bracket formed with a plurality of vertically aligned openings mounted on the gate, a pivot member extending through an opening in the ear on said housing adapted to be extended through any one of the openings in said bracket, for adjustably attaching the housing thereto for a pivotal movement thereon, a guide bracket mounted on the gate for guiding the housing in its pivotal movement on the first mentioned bracket, an arm slideable in the housing formed with a plurality of ratchet teeth having one end extending beyond the housing and pivotally connected with one of the post carried elements, and a latch carried by the housing for engagement with the ratchet teeth on said arm for holding said arm in an adjusted position relative to the housing whereby the gate is secured in adjusted position relative to the parts for pivotal movement thereon.

In testimony whereof I affix my signature.

OTTO K. BINDER.
